UNITED STATES PATENT OFFICE

153,507

DESIGN FOR A FOUNTAIN BRUSH HEAD

John Drubko, Jefferson, Ohio

Application November 16, 1948, Serial No. 149,649

Term of patent 14 years

(Cl. D49—1)

To all whom it may concern:

Be it known that I, John Drubko, a citizen of the United States, and resident of Jefferson, county of Ashtabula, and State of Ohio, have invented a new, original, and ornamental Design for a Fountain Brush Head, of which the following is a specification, reference being had to the accompanying drawings, forming part thereof.

Fig. 1 is a perspective view of a fountain brush head, showing my new design;

Fig. 2 is a top plan view thereof; and

Fig. 3 is a side elevation thereof.

The dominant features of my design reside in those portions shown in full lines.

I claim:

The ornamental design for a fountain brush head, as shown and described.

JOHN DRUBKO.
